DESIGN FOR A CARPET-PATTERN.

Specification forming part of Design No. 5,166, dated August 8, 1871.

To all whom it may concern:

Be it known that I, ROBERT R. CAMPBELL, of the city of Lowell, county of Middlesex and State of Massachusetts, have invented and produced a new and original Design for a Pattern to be inwrought into Two or Three-ply, Ingrain, and other Carpeting in such colors as may be desired; and I do hereby declare that the photographic prints accompanying this specification do give and convey, to any one skilled in the art of carpet-weaving, a more definite and thorough description of the nature of my invention than it is in the power of language otherwise to convey, and they are suf-

ficient to enable any one skilled in the art of carpet-weaving to use my invention.

What I claim as my invention, and desire to secure by Letters Patent, is—

The configuration of the design hereunto annexed, when made by being inwrought into two or three-ply, ingrain, or other carpeting in the form similar to the photographic prints accompanying this specification.

R. R. CAMPBELL.
